UNITED STATES PATENT OFFICE.

ELMER L. OGLE, OF NEW YORK, N. Y., ASSIGNOR TO N. LEROY OTIS, OF NEW YORK, N. Y.

RADIATOR.

No. 873,384.

Specification of Letters Patent.

Patented Dec. 10, 1907.

Application filed October 8, 1906. Serial No. 337,887.

To all whom it may concern:

Be it known that I, ELMER L. OGLE, a citizen of the United States, residing at New York city, in the county of New York and State of New York, have invented new and useful Improvements in Radiators, of which the following is a specification.

My invention relates to coolers or radiators for dissipation or rapid equalization of temperatures in liquids, gases or vapors, and it has for its object the improvement in efficiency and lightness of such radiators, the cheapening of their manufacture and the prevention of ill effects resulting from differences in temperature therein, and also has for its object the manufacture of certain of its parts without unduly straining or exposing the metal from which they are made, or opening the joints where such parts are seamed or jointed. Furthermore, the cooler is so built and arranged that in case of leak it may be quickly stopped by simply plugging each end of the tube.

To illustrate one form in which my invention may be embodied the accompanying drawings are furnished which form a part hereof and in which

Figure 1. represents a perspective view of the cooler assembled, Fig. 2. is a section of a part of the cooler showing the grouping of certain square tubes forming the body of the cooler. Fig. 3. is a horizontal section through a part of the cooler. Fig. 4. is a vertical section of a portion showing the deflectors and a portion of the perimeter or shell. Fig. 5. is a section view showing a construction of the deflector. Fig. 6. is a front view of one form of the cooler. Fig. 7. is a detail of the off-set lock joint in one of the tubes.

Within the casing or shell "A" is secured a group of comparatively short polygonal tubes "a" through which air or other cooling medium may pass and between which the liquid to be cooled may circulate in thin films and in either straight or broken and zigzag vertical courses. To create these spaces "b" between the tubes "a" I enlarge one end of each tube and then place them side by side alternately as to ends and solder these ends together. These tubes "a" must be thin and consequently fragile if they are to be efficient.

In my cooler I do very little enlarging of the tubes and this at one end only confining the enlarging to opposite, usually two sides of one end only. I can thus use thinner

tubes for my purpose. With thinner tubes, a higher cooling efficiency and a lighter cooler may be constructed which is perfectly rigid and reliable as to construction. With this arrangement it is also possible to use seamed or jointed tubes "a" made up of very thin copper or other ribbon, the enlargement "c" not necessarily coming at the joint itself. The tubes are arranged as stated or they may be assembled in layers or rows and the row as such disposed horizontally in such manner that it is possible to shift laterally a whole row so that all of the spaces may come directly above the centers of the tubes below, securing the very valuable arrangement of the vertically off-set passages "b" within the body of the cooler as seen in Fig. 2. When the tubes are laid up in courses spacers may be used as shown in Fig. 4, "g" being a plain spacer "g" a projecting spacer, the projection of which may be employed as a deflector for the air. A filler "g'", (see Fig. 5.) is provided for the open side of the deflector. The tubes are solidly soldered at their ends. To produce a cooler which will withstand high pressures I find that this soldering should be very deep and thorough, and to accomplish this I first found it necessary to tin each end of each tube.

When tubes are employed that are seamed as above described, the seam may be off-set inwards so as to give a smooth surface on the exterior of the tube. (See Fig. 7). It can readily be seen that the tubes may be many sided or even round with squared or polygonal ends, the squared ends being preferred.

The operation of the device is evident from the foregoing description. Its primary use is for the rapid dissipation of heat, this being accomplished by first dividing the heated medium into thin layers between very thin cooled walls and cause circulation in irregular courses so as to bring different portions of the medium to be cooled into contact with such walls. The walls should be thin so as to instantly transmit and dissipate the heat.

The casing or shell "A" is provided with suitable inlet and discharge openings as "BB". (See Figs. 1 and 4.)

For the purpose of illustration I have described one construction of my improved cooler. I do not wish to be limited to any exact detail or arrangement of parts shown as others may be employed and some omitted and the invention extends to such use.

Having fully described my invention: I claim:

1. A cooler comprising polygonal tubes having a longitudinal seam on one flat side 5 provided with a rectangular enlargement at one end only and grouped alternately so as to leave spaces between such tubes, substantially as described.
2. A cooler comprising square tubes having a longitudinal seam on one flat side, the seam being brought flush on the exterior at the ends of the tube, the tubes enlarged on two opposite unseamed sides at one end and grouped alternately in layers or rows so as to 15 leave spaces between such tubes, substantially as described.
3. A cooler comprising square tubes enlarged on two opposite sides at one end and grouped alternately into rows, the rows laid 20 one upon the other with spacers between the ends of the tubes of each row.
4. A cooler comprising tubes enlarged on two opposite sides at one end and arranged alternately to leave spaces between such tubes, grouped in layers or rows and an air deflector between the rows at the face of the cooler. 25
5. A cooler comprising square tubes enlarged at one end upon two opposite sides grouped alternately into rows so as to leave spaces between each tube in the row, the rows laid one upon the other so that the tubes of a given row are vertically above the space in the row below with spacers between the ends of the tubes of each row. 30

In testimony whereof I have hereunto set my hand in presence of two subscribing witnesses.

ELMER L. OGLE.
